Attorney.

UNITED STATES PATENT OFFICE.

MONTE H. BOSE, OF INDIANAPOLIS, INDIANA.

RADIATOR PET-COCK ATTACHMENT.

1,422,919.

Specification of Letters Patent. Patented July 18, 1922.

Application filed October 28, 1921. Serial No. 511,142.

To all whom it may concern:

Be it known that I, MONTE H. BOSE, a citizen of the United States, residing at Indianapolis, in the county of Marion and State of Indiana, have invented new and useful Improvements in Radiator Pet-Cock Attachments, of which the following is a specification.

Pet-cocks for draining auto-car radiators are located underneath and so near to the middle of the radiators that they are not readily accessible, and the object of this invention is to provide a bar-attachment to the cock which extends outside of the chassis-frame and terminates with an enlargement for convenient manipulation.

I accomplish the above and other objects which will hereinafter appear, by the mechanism illustrated in the accompanying drawing, in which—

Fig. 1, is a front elevation of an automobile radiator with my invention operatively installed. Fig. 2, is a view of same in side elevation and partial vertical section, and Fig. 3, is a perspective view of my attachment, removed.

The chassis-frame 4, radiator 5, and radiator drain cock 6, are of any suitable and usual construction wherein the stem of the cock has a handle, usually in the form of wings, as a hand-hold for opening and closing the cock. This, as shown, is usually well in on the radiator bottom from the side of the chassis-frame where it is inconvenient to reach for manipulation. I therefore provide an extension bar 7 which is supported by a bracket 8 bolted to the side frame of the chassis, as shown. The bar has a bifurcated end 9 between the forked members of which the handle of the cock 6 is received and held in a manner to open and close the cock when the bar 7 is rocked.

The outer end of the bar 7 is provided with suitable means, here shown as wings 10, for grasping, in the rocking of the bar.

The bracket 8 is here shown as formed from strap metal having one end bent at right angles to form the member 11, and again at right angles to form the member 12. Holes in alinement are provided as shown to receive the bar which is journaled therein

and which is held against longitudinal displacement by cotter-pins 13 and 14.

The opposite end of the bracket is bent on a line oblique to the longitudinal dimensions 55 of the body portion whereby the member 15 is at right angles to said body of the bracket with the result that when member 15 is against the bottom of the chassis-frame the body of the bracket is enough downwardly 60 oblique to bring the bar 7 level with the valve stem of the cock 6. The member 15 has a longitudinal slot 17 for a bolt securing the bracket to the frame. The slot allows for adjustment of the bracket longitudinally 65 of the frame to aline the bar 7 with the stem of the drain cock.

It will thus be seen that the bar extension terminates with wings 10 outside of the chassis-frame where it is easily reached and 70 manipulated for opening and closing the radiator drain cock.

Having thus fully described my invention, what I claim as new and wish to secure by Letters Patent of the United States, is— 75

1. A bar having a recessed end to operatively engage the handle of a radiator drain cock and having a hand-hold at the opposite end for manipulating the bar, in combination with a bracket for supporting the bar 80 formed of strap metal having a return bend at its lower end forming a double support for the bar, and having its upper end bent and adjustably secured to a supporting member. 85

2. A bar having a recessed end to operatively engage the handle of a radiator drain-cock, and having a hand-hold at the opposite end for manipulating the bar; in combination with a bracket for supporting 90 the bar formed of strap metal having a bend at right angles near its lower end, and a second bend bringing the end parallel with the body of the bracket and forming a double support for the bar; means to prevent 95 longitudinal movement of the bar in the bracket, said bracket having its upper portion slotted and bent laterally and bolted through the slot to a supporting member.

Signed at Indianapolis, Indiana, this the 100
25th day of October, 1921.

MONTE H. BOSE.
